UNITED STATES PATENT OFFICE.

ADOLPH J. CHAUVIN, OF MORGAN CITY, LOUISIANA.

NON-SINKABLE BOAT.

1,220,955.

Specification of Letters Patent. Patented Mar. 27, 1917.

Application filed October 9, 1916. Serial No. 124,583.

To all whom it may concern:

Be it known that I, ADOLPH J. CHAUVIN, a citizen of the United States, residing at Morgan City, in the parish of St. Mary and State of Louisiana, have invented certain new and useful Improvements in Non-Sinkable Boats; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in hulls for boats and the object in view is to produce a substantial craft of this nature so arranged that, in the event of the hull being punctured at different locations, any water which may leak inside the hull will be confined in compartments, reinforced by a central longitudinal beam.

The invention consists of a simple and efficient apparatus of this nature having various details of construction, combinations, and arrangements of parts which will be hereinafter fully described, shown in the accompanying drawings and then specifically defined in the appended claims.

I illustrate my invention in the accompanying drawings, in which:—

Figure 1 is a central vertical sectional view through a hull made in accordance with my invention.

Fig. 2 is a transverse longitudinal section, horizontally through the boat hull.

Reference now being had to the details of the drawings by letter, A designates the hull of the boat, which may be of any suitable material, and B are series of transverse partitions extending the entire width of the boat and spaced apart suitable distances. Angle beams C are fastened to the opposite side walls and to the bottom of the hull and to which the entire marginal edges of the partitions are securely fastened. A brace beam D extends centrally through the various partitions from stem to a point rearward of the center where it branches,

forming two sections E and F which extend to the extreme stern of the boat and, at the locations where the brace B passes through the partition, reinforcing angle irons H are utilized which serve as means for fastening the brace to the partitions.

By the provision of a hull made in accordance with my invention, it will be noted that a substantial and rigid hull is afforded which, in the event of being punctured at any location along its sides, will still keep afloat, any water which may fill one or several of the compartments not being sufficient to prevent the boat from floating.

What I claim to be new is:—

1. A hull construction for boats having a series of transverse partitions, spaced apart and extending the entire length of the hull, a brace beam extending centrally through the various partitions and having a forked portion which passes through said partitions.

2. A hull construction for boats having a series of transverse partitions, spaced apart and extending the entire length of the hull, a brace beam extending centrally through the various partitions and having a forked portion which passes through said partitions, and angle irons secured to the inner surface of the wall of the hull and to which the partitions are secured.

3. A hull construction for boats having a series of transverse partitions, spaced apart and extending the entire length of the hull, a brace beam extending centrally through the various partitions and having a forked portion which passes through said partitions, angle irons secured to the inner surface of the wall of the hull and to which the partitions are secured, and angle irons on opposite sides of the forked portion of the brace beam and secured thereto and to said partitions.

In testimony whereof I hereunto affix my signature in presence of two witnesses.

ADOLPH J. CHAUVIN.
